UNITED STATES PATENT OFFICE.

DANIEL B. LUTEN, OF INDIANAPOLIS, INDIANA.

CONCRETE-REINFORCEMENT.

1,078,510.

Specification of Letters Patent.

Patented Nov. 11, 1913.

Application filed September 25, 1906. Serial No. 336,157.

To all whom it may concern:

Be it known that I, DANIEL B. LUTEN, a citizen of the United States, residing at Indianapolis, in the county of Marion and 5 State of Indiana, have invented certain new and useful Improvements in Concrete-Reinforcement, of which the following is a specification.

In the building of reinforced concrete 10 floors, arches and the like the labor employed is comparatively unskilled and, as the proper placing of the reinforcement is very important in order to secure desired results with a minimum weight of reinforcing material, 15 difficulty has heretofore been experienced in placing the reinforcing material properly.

The object of my present invention is to produce a reinforcing unit properly designed 20 for a particular structure in view, with the several parts thereof so formed that when associated in a unit, the various stresses to which the completed structure will be subjected will be properly taken care of with a 25 minimum weight of reinforcing material, the construction being such that the several parts may be properly formed in a factory where proper tools are ready at hand, and such that the unit may be shipped either in its 30 completed form or may be shipped in "knocked down" form and readily assembled by unskilled labor.

A further object of my invention is to so 35 form a reinforcing unit of the class described that the stresses will be applied thereto symmetrically so as to avoid producing material turning moments on the unit.

The accompanying drawings illustrate my invention.

40 Figure 1 is a vertical section of a floor and supporting abutments or partitions, constructed in accordance with my invention; Fig. 2 a section, on a smaller scale at right angles to Fig. 1; Figs. 3 and 4 similar sections of multiplied constructions wherein tiling is used in part for the floor; Fig. 5, a perspective view of a 3-element unit; Fig. 6, a similar view of a 5-element unit; and Fig. 7 a perspective detail of a suitable form of 50 clamping member.

In Fig. 5 I show a 3-element unit consisting of a central rod 10 which extends the length of the unit, *i. e.* from beam 11 to beam 12. Laid alongside of element 10 upon each side thereof are the rods 10' and 10''. The rod 10' at the point A is bent upwardly

and at the point B brought again substantially parallel with the middle portion of the element and continued from the point B to the point C where it is bent downward, the 60 end of the element being sufficiently long to extend a considerable distance into the depth of the far-side of the support. The element 10'' is similarly bent upward at the point A' and then at the point B' brought parallel 65 with the middle portion of the element and at the point C' turned downward in the manner already described for the rod 10'. That portion of element 10' between A and B lies nearer to the transverse middle of the 70 unit than does the portion between A' and B' of the element 10'' and, in order to lie more nearly at right angles to the shearing forces acting within the floors, the angle of 75 the portion between A and B to the horizontal is greater than is that of the portion between A' and B' to the horizontal. The elements 10, 10' and 10'' are secured together by a suitable clamp at various points. The elements 10' and 10'' are placed upon opposite 80 sides of element 10 in order that there may be no measurable turning moment of force acting on the reinforcing unit.

In the unit shown in Fig. 6 the central element 20 is bent upwardly at the point 85 201 and at the point 202 brought into parallelism with the middle portion. Flanking the element 200 are the elements 21 and 22. The element 21 is bent upward at the point 90 211 and at 212 is brought into parallelism and at 213 is turned downward so as to extend 95 downward along the far-side of the partition or abutment 13. If the support for the beam is a retaining wall as at 14, the down-turned end of the element 21 may be left of sufficient length so that at the point 100 214 it may be bent inward and crossed over toward the inner face of the retaining wall and at 215 continued downward along the inner face of the retaining wall, the point 105 of flexure in the retaining wall being approximately the neutral shear zone so that the reinforcing rod will lie in the region of tension adjacent the outer face of the retaining wall at its outer end and in the region of tension adjacent the inner face at a point lower down. The element 22 is bent upwardly at 221, at 222 is brought into parallelism, and at 223 is turned down in the vertical plane of the down turned end of element 21. Lying alongside and outside of 110 the elements 21 and 22 are elements 23 which

lie outside the vertical planes of the middle staggered portion of elements 20, 21 and 22 and at their ends are provided with hooks 23 adapted to receive the down turned end 5 of the elements 21 and 22. Point 201 is nearer the transverse middle of the unit than are the points 211 and 221 and the angles between the horizontal and the portions 201—202, 211—212, and 221—222 are gradually increased for the reason already mentioned.

Any suitable clamping means may be employed for connecting the several elements of a reinforcing unit together, a convenient 15 clamp being shown in Fig. 7 which clamp is similar to the clamp shown in my prior Patent No. 1,060,919, patented May 6, 1913. This clamp consists of a piece of sheet metal 30 bent into a U and provided with notches 20 31 at the base of the U to receive the elements 20, 21, 22 and 23. Notches 31 are of gradually decreasing depth from one end 25 of the sheet to the other and a wedge 33 is inserted in the base of the U between it and the inserted rods or unit members. The 30 wedge may be conveniently formed by bending a tapered sheet into a U-shape. The slots 31 may be formed by punching and in one or more of the slots a portion may be 35 left and this portion may be bent out of the slots so as to form a downwardly extending tooth or prong 34 which may be driven into the centering to hold the unit in proper position above the centering, the construction being such that, when the centering is removed the tip of the prong will be exposed so that the metal lathe can be secured thereto very readily.

I claim as my invention:

40 1. A reinforcing unit for beams supported on columns, comprising a plurality of longitudinal members for embedment in the beam, said longitudinal members being spaced transversely and connected by members defining said spacing, the ends of some of 45 said longitudinal members being vertically displaced upward, with the ends of said upwardly displaced members returned to substantial parallelism with the undisplaced members and then bent downward and crossing 50 the plane of the undisplaced members and extending below the plane of the bottom of the beam for embedment in the supporting columns.

2. A reinforcing unit to be embedded in 55 beams and supporting columns of concrete, said unit having a main portion for embedment in the beam, the ends of which main portion have a greater vertical height than its middle and also have downward extensions which extend below the bottom plane of the main portion and of the beam for embedment in the supporting columns.

3. A reinforcement unit intended for beams supported on columns, comprising a 65 plurality of longitudinal members connected by other members arranged transversely of the unit, certain of said longitudinal members being vertically displaced upward at points varying in distance from the middle 70 of the unit and thereafter brought into substantial parallelism with the undisplaced members, the ends of upwardly displaced members being down turned and crossing the plane of the undisplaced middles of the 75 members and extending below the plane of the bottom of the beam for embedment in the supporting columns.

4. A reinforced plastic structure comprising vertical supporting members, connecting 80 members resting on said supporting members, and reinforcing members extending through low regions in the connecting members at intermediate portions in the length of the latter, deflected thence upward to 85 extend through higher regions in the connecting members adjacent the supporting members, and deflected thence downward below the plane of the connecting members 90 into the supporting members, the said downwardly extending parts of a reinforcing member lying in those portions of the supporting members farthest from the connecting member in which the main portion of 95 said reinforcing member lies, whereby the reinforcing members extending into a supporting member from the connecting members on opposite sides thereof cross each other.

In witness whereof, I have hereunto set 100 my hand and seal at Indianapolis, Indiana, this 20th day of September, A. D. one thousand nine hundred and six.

DANIEL B. LUTEN. [L. s.]
